US00D838022S

(12) **United States Design Patent** (10) **Patent No.:** **US D838,022 S**
Leegate et al. (45) **Date of Patent:** **** Jan. 8, 2019**

(54) MARKER SYSTEM	7,322,205 B2 *	1/2008 Bourne	F24F 3/044 62/305
(71) Applicant: ARCACHON HOLDINGS LLC , Clearwater, FL (US)	7,505,279 B2	3/2009 Ohtaki et al.	
	7,722,205 B2	5/2010 Kim	
	7,831,150 B2	11/2010 Roes et al.	
	D638,964 S *	5/2011 Cappuccio	D26/39
(72) Inventors: Gary Leegate , Clearwater, FL (US); Marcia Baldwin , Clearwater, FL (US)	8,269,619 B2 *	9/2012 Lee	A42B 3/0453 340/432
	8,477,492 B2	7/2013 Rothkopf et al.	
	8,485,686 B2	7/2013 Swan et al.	
	8,534,861 B2	9/2013 Leegate et al.	
	8,573,797 B2	11/2013 Spartano et al.	
	8,672,504 B2	3/2014 Kramer	
(73) Assignee: ARCACHON HOLDINGS LLC , Clearwater, FL (US)	2008/0216699 A1	9/2008 McAleer et al.	
(**) Term: 15 Years	2010/0128468 A1	5/2010 Ong et al.	
(21) Appl. No.: 29/608,710			
(22) Filed: Jun. 24, 2017			
(51) LOC (11) Cl. 26-02			
(52) U.S. Cl.			
	USPC	D26/39	
(58) Field of Classification Search			
	USPC	D10/46; D26/37-41, 51, 60	
	CPC	A42B 3/044; A42B 3/0453; B60Q 1/2676;	
		B60Q 2900/30; B62J 6/005; B62J	
		2006/008; F21V 24/08; F21V 21/0885;	
		Y10T 29/49895
